UNITED STATES PATENT OFFICE.

DUNCAN McMILLAN, OF BROOKLYN, NEW YORK.

FINGER-GUARD.

SPECIFICATION forming part of Letters Patent No. 718,652, dated January 20, 1903.

Application filed August 9, 1902. Serial No. 119,116. (No model.)

To all whom it may concern:

Be it known that I, DUNCAN McMILLAN, a citizen of the United States, residing at Brooklyn, in the county of Kings and State of New York, have invented new and useful Improvements in Finger-Guards, of which the following is a specification.

The invention relates to finger-guards to be worn upon the finger of a person and designed for use in pressing or packing down the tobacco in a lighted pipe, whereby the finger will be prevented from being burned.

The object of the invention is to provide a device of this character which shall be simple of construction, durable in use, comparatively inexpensive of production, and efficient in action.

To this end the invention consists in certain novel features of construction and combination and arrangement of parts, which will be hereinafter fully described and claimed, and illustrated in the accompanying drawings, in which—

Figure 1 is a perspective view of the improved finger-guard. Fig. 2 is a longitudinal vertical sectional view through the same. Fig. 3 is a view of a modified form.

The device consists of a cap 1, designed to be slipped upon the end of the finger. The cap, as shown in Figs. 1, 2, and 3, may be made of a flexible material, preferably elastic and preferably consisting of rubber. When made of flexible elastic material a button 2 is provided. As shown in Figs. 1 and 2, the button may project from the side of the cap, or, as shown in Fig. 3, may project from the end of the cap. In either case the button is supposed to be of a size to fit

the bowl of the pipe, whereby the lighted contents of the bowl may be pressed downward to render the same compact.

It is evident that the device will prevent the finger from becoming burned.

From the foregoing description, taken in connection with the accompanying drawings, it is thought that the construction, operation, and advantages of my improved finger-guard will be readily apparent without requiring a more extended explanation.

Various changes in the form, proportion, and the minor details of construction may be resorted to without departing from the principle or sacrificing any of the advantages of this invention.

Having thus described my invention, what I claim as new, and desire to secure by Letters Patent, is—

1. A finger-guard for the purpose described, consisting of elastic cot to fit the finger and provided with a metallic button at its tip, substantially as described.

2. A finger-guard for the purpose described consisting of a flexible cot having attached thereto intermediate the ends thereof a button substantially as described.

3. A finger-guard for the purpose described consisting of a flexible elastic cot, having a button attached thereto intermediate the ends thereof, substantially as described.

In testimony whereof I have hereunto set my hand in the presence of two subscribing witnesses.

DUNCAN McMILLAN.
